(57) **CLAIM**

The ornamental design for a faucet handle, as shown and
described.

DESCRIPTION

FIG. 1 is a perspective view of a faucet handle showing my
new design;

FIG. 2 is a top plan view thereof;

FIG. 3 is a side view thereof; and,

FIG. 4 is a bottom view thereof.

The broken line shown in FIG. 4 of the drawings is included
for the purpose of illustrating a portion of the faucet that
forms no part of the claimed design.
